BURNER

Owen L. Appleby, San Jose, Calif.

Application April 9, 1936, Serial No. 73,459

1. Claim. (Cl. 158—77)

The present invention relates particularly to burners adapted for use in burning gas or oil, or both, under boilers or in other desired associations.

5 It is one object of the present invention to provide a burner assembly of the character indicated so constructed and arranged that complete combustion of the fuel is effected and the combustion chamber maintained substantially free from all 10 carbon deposits.

Another object is to provide an assembly operable in such a manner that the flames are at all 15 times automatically prevented from working back into the blower chamber or other parts of the assembly rearwardly of the combustion chamber.

Still another object of the invention is to provide an assembly of the character indicated so constructed and arranged that heat from the combustion chamber cannot travel by conduction 20 to the rearward portions of the structure.

Finally, it is an object to provide a burner assembly that will be economical to manufacture, simple in form and construction, that consists of few parts, and that is substantial, durable, and 25 highly efficient in its practical application.

In the drawing:

Figure 1 is a side elevation of an assembly embodying my invention, partly in section.

30 Figure 2 is a section on line 2—2 of Figure 1.

Figure 3 is a section on line 3—3 of Figure 1.

Figure 4 is a section on line 4—4 of Figure 1.

In the particular embodiment of the invention herein disclosed, I show at 1 a base upon which 35 an electric motor 2 is mounted, the motor drive shaft showing in part at 3.

Cast integrally with base 1 and at right angles thereto is an upstanding annular member 4 having an air passage 5 formed therein in axial alignment with the said shaft 3. This member also has other segmental air passages formed therein and arranged about its axis as at 6, the air flow through these passages being controlled by a damper 7. Passages for feeding fuel gas through 40 the burner are shown at 8, these passages being spaced one hundred and twenty degrees apart and radially arranged relative to its axis, and discharging through the face of the member as at 9 adjacent the circle defining the inner edges of 45 the passages 6. A portion of the member 4 is thickened as at 10 and an annular passage 11 is formed therein to connect the three passages 8.

50 Gas may be fed into the burner through one passage 8 as at 12 while the other passages 8 are closed by plugs 13, or it may be fed through two

or all three of the passages 8 if a larger capacity is desired.

On the member 4 is formed a boss 15, this boss having an overhanging and forwardly projecting portion 16 through which a conduit 17 passes, the 15 conduit discharging downwardly as at 18 near its forward end into a tube 19. If the burner is to be used for burning oil the oil is fed into the conduit 17 through a pipe 20 from a source of supply not shown. When the device is used as an oil burner 10 all three gas passages 8 are closed.

On the forward face of member 4 and in concentric relation to the axis of rotation of shaft 3 is formed an annular flange 21, and within this flange is seated an annular member 22 of heat insulating material such as an asbestos-cement composition.

In the forward edge of member 22 is formed an annular seat 23. At 24 is a cylindrical member forming a combustion chamber 25, this member having one end formed as at 26 to engage seat 23. Tie rods as 27 are mounted in member 24 and pass through member 4 and are secured by nuts as at 28, thereby binding the member 4, member 22, and member 24 into one unitary structure. 20 25

The front end of member 24 is open as at 29, and the rear end has arcuate slots as 30 formed therein in concentric relation to the axis of rotation of shaft 3, the outer edges of these slots 30 aligning with the outer edges of the passages 6. A circular opening 31 is also formed in this end of member 24 in concentric relation to said axis, this opening having substantially the same diameter as air passage 5 in member 4. 35

At 32 is shown a blower spindle seated on the end of the motor shaft 3 and to which it is secured by set screw 33. The forward portion of spindle 32 flares outwardly somewhat as at 34 and terminates in a flange 35, the forward end 40 of the spindle being flat as at 36. The tube 19 is disposed to discharge against the rear of flange 35 adjacent the spindle 32 so that oil discharged therefrom onto the flange will be thrown outwardly and atomized by the centrifugal force 45 generated by the rapidly rotating spindle.

Formed integrally with the spindle 32 are vanes 37. These vanes 37 are disposed to rotate in the blower chamber 38, the bases of the vanes being joined directly to the spindle on each edge so 50 that air may flow along the spindle between them.

When the burner is in operation, burning fuel oil, the oil is discharged and vaporized as described. Since the vaporizing end of the spindle 55

is integral with the vanes it follows that the air flow is simultaneous with the discharge of oil. The air is drawn into the burner through passage 5, flowing along the spindle 32 to the vanes 37.

5 The vanes are so formed that the air so drawn in is discharged forwardly along the spindle and out into the combustion chamber through passage 31, mixing with the oil as it passes flange 35. Air is also fed into the blower chamber 38

10 in desired quantities through passages 6, and allowed to discharge from chamber 38 through the slots 30 where it mixes with the oil-air mixture from 31 and 35.

The result of this construction and arrangement is, that when the burner is in operation there is a continuous flow of air along the spindle and out into the combustion chamber through

15 passage 31, and consequently there is no possibility of the flames working back into the blower chamber through passage 31. Likewise, there

20 must be, and is, a constant flow of air outwardly through slots 30, with like effect. The said chamber 38 is, therefore, completely protected against invasion by burning oil or gases from chamber

25 25, and since the enclosing peripheral wall 24 of this chamber is made of heat insulating material it follows that all of the rear portion of the burner, including the motor and spindle, is protected against damage by heat. The air flowing

30 forwardly along the spindle 32 will, of course, act as a cooling agent therefor.

Another result of this construction and arrangement is that when the air is discharged into the combustion chamber 25 it takes on a rolling

35 motion, due perhaps to the fact that the stream of air entering through the passage 31 is whirl-

ing at a high rate of speed, while the air entering through slots 30 is whirling at a different rate of speed, the meeting of the two streams so completely and thoroughly atomizing and mixing the oil that complete combustion takes place 5 and no carbon deposits are made on the walls of the chamber.

By placing the pipe 19 as described it absorbs heat from the combustion chamber and thereby assists in preparing the oil for atomization. 10

It is to be understood, of course, that while I have herein shown and described but one specific embodiment of the invention, changes in form, construction, and method of assembly and operation may be made within the scope of the ap- 15 pended claim.

I claim:

A fluid-fuel burner of the character described comprising, axially aligned blower and combustion chambers, a partition between the chambers 20 provided with a central passage and with other passages radially spaced therefrom, the blower chamber having an air supply passage leading thereto, a rotating spindle extending through the central passage in spaced relation to its walls, 25 vanes associated with the spindle and disposed in the blower chamber to force air through said passages to the combustion chamber, said spindle terminating in a radially directed fluid-fuel spreader flange disposed in the combustion chamber to discharge fluid-fuel radially into the path of travel of air discharged through the radially spaced passages and a fluid-fuel feed conduit disposed to deliver fluid fuel to the base of said spreader flange. 30
